OSCILLATORY DRIVE FOR SLIVER RECEIVING CANS

Baldy McGinnis, Roswell, Ga., assignor of one-half to R. A. Carruth, Roswell, Ga.

Application June 8, 1938, Serial No. 212,561

7 Claims. (Cl. 19—159)

This invention relates to an oscillatory drive for sliver receiving cans used in connection with cotton drawing machines.

The object of the invention is to provide, in a manner as hereinafter set forth, a drive for the purpose referred acting to reversely revolve the can, at each complete revolution of the latter to overcome the slight twist or turn ordinarily put on the coils during drawing of the sliver, thereby resulting in the affording of ease and expedition in the uncoiling of the sliver when spinning.

The invention has for its further object to provide, in a manner as hereinafter set forth, a drive 15 of the class referred to which is simple in its construction and arrangement, strong, durable, compact, readily installed with respect to a cotton drawing machine and a sliver receiving can associated with such machine, thoroughly efficient 20 in its use, conveniently assembled and comparatively inexpensive to manufacture.

Embodying the objects aforesaid, and to others which may hereinafter appear, the invention consists of such parts and such combinations of parts as will be more specifically referred to and as 25 illustrated in the accompanying drawings, wherein is shown an embodiment of the invention, but it is to be understood that changes, variations and modifications may be resorted to which fall 30 within the scope of the invention as claimed.

In the drawings:—

Figure 1 is a fragmentary view partly respectively in vertical section, in side elevation and broken away of the cotton drawing machine, the sliver can associated with the latter, and the oscillatory drive, in accordance with this invention installed with respect to said machine and can,

Figure 2 is a vertical sectional view of the drive broken away,

Figure 3 is a vertical sectional view of the drive, broken away and taken at right angles to the showing of Figure 2,

Figure 4 is a section on line 4—4 Figure 2,

Figure 5 is a section on line 5—5 Figure 4,

Figure 6 is a section on line 6—6 Figure 3, and

Figure 7 is a plan view of the gear train for revolving the can support.

With reference to Figure 1 of the drawings 50 there is shown an apertured coiler plate 1, a peripherally toothed revoluble coiler 2 in the aperture of and slidably coupled to plate 1, a driving means 3 for coiler 2 connected to and arranged over the plate 1, and an operating means 4 for the driving means 3 arranged over plate 1

and meshing with the means 3. The plate 1, coiler 2, driving means 3 and operating means 4 are elements which correspond in form to like elements of cotton drawing machines now in general use. There is associated with and arranged below the coiler 2 a driven revoluble open top can 5 for receiving the sliver from the coiler. The latter revolves at a greater speed than the can. The foregoing elements are of known construction and are illustrated for the purpose of 10 showing the drive, in accordance with this invention installed with respect to the machine and can.

The oscillatory drive, in accordance with this invention for the can 5 acts to reverse the direction of movement of the latter after each substantially complete revolution of the can to obtain the object as aforesaid when coiling the sliver. The drive includes a power transmission which takes off from the driven shaft 6 of the 20 operating means 4 for the coiler 2. The power take-off transmission includes a bevel pinion 7 fixed to shaft 6, a bevel pinion 8 meshing with the driven pinion 7 and a vertically disposed shaft 9 extending through and depending from the platform or the plate 1 adjacent the coiler 2. The shaft 9 lengthwise of its periphery is formed with a groove 10, and is also formed at its lower end with an adjustable stop collar 11.

The drive includes a combined carrying and revolving mechanism 12 for the can 5. The mechanism 12 includes a vertically disposed rotatable shaft 13, a gear train 14 consisting of a pair of horizontally disposed spaced aligned gears 15, 16 of different diameters and an intermediate gear 17 of less diameter than, aligning with, arranged between and meshing with the gears 15, 16, an upstanding revoluble shaft 18 fixed to gear 15, and a revoluble flanged carrier element 19 fixed to the upper end of shaft 18. The bottom portion 30 of can 5 is fixed in the element 19, the latter bodily revolves the can therewith. The gear 17 is revoluble about a hanger shaft 20. The gear 15 and the major portion of gear 17 are arranged in a closed top and open bottom housing 21. The shaft 18 extends upwardly through the shaft 20 35 depends from and bearings 22 depend from the top of housing 21 for shafts 18, 20. Retaining collars 23 are secured to the lower ends of shafts 18, 20. A spacer 24 is interposed between element 19 and housing 21. The latter at one side is open 40 for the passage of a part of the gear 17. The gear 16 is fixed to the lower end of shaft 13. The latter is arranged within and axially of an upstanding closed top and bottom cylindrical cas- 45

ing 25 disposed in horizontal aligned spaced relation with respect to can 5. The top 26 and the bottom 27 of the casing 25 have secured to their inner faces oppositely disposed bearings 28, 29 respectively in which the ends of shaft 13 are positioned. The casing 25, at one side is formed with a cut-out 30 for the passage of gear 17 to mesh with the gear 16. The latter is of less diameter than the gear 15.

10 The drive includes a reversible driving mechanism 31 for the combined carrying and revolving mechanism 12 for the can 5. The mechanism 31 consists of a split annular mangle rack 32 having oppositely rounded ends 33, 34. The rack 32 includes an upper set 35 and a lower set 36 of beveled continuous teeth. The sets 35, 36 extend from one end to the other of the rack 32 and merge into the teeth 37 formed on the rounded ends 33, 34 of the rack. The teeth 37 are beveled and form continuations of the teeth of the sets 35, 36. The rack 32 is arranged within the casing 25 between the transverse median of the latter and its upper end. The rack 32 is suspended from a combined guide and retainer structure 38 positioned within casing 25, disposed inwardly of, above and below the rack 32 in spaced relation to the latter. The structure 38 includes an upper combined guide and retainer portion 39 in the form of a split annulus, a lower 20 combined guider and retainer portion 40 in the form of a split annulus and a pair of oppositely disposed curved upstanding vertically disposed combined guides, retainers and coupler portions 41, 42. The portions 39, 40 at one end merge 25 into the ends of the portion 41. The portion 39, 40 at the other end merge into the ends of the portion 42. The portions 39, 40 are spaced inwardly with respect to the sets of teeth 35, 36 respectively. The portions 41, 42 are spaced inwardly with respect to the teeth on the rounded ends 33, 34 respectively. The rack 32 is connected to the structure 38 by radially disposed spaced couplers 43 which are integral with the inner face of rack 32 and the outer side surfaces 45 of upstanding outwardly opening spaced curved yokes 44 having their ends integral with the inner side faces of the portions 39, 40 of structure 38. The latter is fixed to the shaft 13, for the purpose of rotating the latter when mechanism 31 is active, by a spider 45 fixed at its center to shaft 13 and at its outer ends to the inner side faces of the yokes 44. The structure 38 and shaft 13 bodily rotate in unison, and for such purpose a rotatable beveled pinion 46 is provided for successively travelling over and engaging with the upper and lower sets of teeth 35, 36 and also for successively travelling over and engaging with the teeth 37 at the ends 33, 34 of the rack. The pinion 46 is carried by a rotatable shaft 48 which is extended inwardly from said pinion. That portion of shaft 48 extended inwardly from pinion 46 carries a combined guide and retainer roller 49. The shaft 48 is extended outwardly from pinion 46 and is journaled in a vertically movable bearing 50 slidably mounted on shaft 9. Fixed to shaft 48, inwardly adjacent to bearing 50 is a bevel gear 51. Keyed to the shaft 9 and slidably mounted on the latter, above the bearing 50 is the hub 52 of a bevel-gear 53 which meshes 55 with and drives the gear 51. Slidably mounted on shaft 9, above the hub 52 is a collar 54, which is connected to the bearing 50, by a laterally extended coupling arm 55. The hub 52 bodily rotates with shaft 9, but is vertically slidable relatively to the latter, and for such purpose, a con-

necting screw or key 56 is carried by the hub 52 and has its inner end terminal portion plain and slidably mounted in the groove 10.

When the pinion 46 is travelling across and engaging with the upper set of teeth 35 of the rack 32, the latter is driven in a clockwise direction carrying shaft 13 therewith in a like direction. When the pinion 46 is travelling across and engaging with the lower set of teeth 34 of the rack 32, the latter is driven in an anti-clockwise direction carrying shaft 13 in a like direction. The pinion 46, when coacting with the upper set of teeth 35 is held in engagement with the latter by the roller 49 travelling against the lower face of the portion 39 of structure 38. The pinion 46, when coacting with the lower set of teeth 36 is held in engagement with the latter by the roller 46 travelling against the upper face of portion 40 of structure 38. It will be assumed with reference to Figure 4, that the pinion 46 is 20 coacting with the upper set of teeth 35 and rack 32 is moving in a clockwise direction, and when rack 32 completes substantially a clockwise revolution, the end 33 of the rack will have reached the pinion 46, the latter will then travel downwardly of the teeth 37 on end 33 of rack 32, engage the lower set of teeth 36 and impart to the rack 32 an anti-clockwise movement. When rack 32 completes substantially an anti-clockwise revolution, the end 33 of the rack will have reached the pinion 46, the latter will then travel upwardly of the teeth 37 on the end 34 of the rack, engage the upper set of teeth 35 and impart to rack 32 a clockwise movement. The pulley 46 as it travels downwardly and upwardly will carry 35 the roller 46, shaft 48, gear 51, bearing 50 and hub 52 therewith but with the gears 51, 52 retained in mesh on the downward or upward travel of pinion 46. Owing to the manner in which the gears 15, 16 and 17 are arranged the can 5 will be 40 revolved at all times in a direction corresponding to the direction in which the rack 32 is revolved.

The cylinder 25 is formed with a vertical elongated slot 57 to provide a clearance for the vertical movement of the shaft 48.

The pinion 46, shaft 48, roller 49, bearing 50, gear 51, bearing 52, gear 53, collar 54 and arm 55 coact to provide a slidably suspended driven means automatically bodily movable in alternate directions in a rectilinear path. The suspension 50 and driving means for said driven means is provided by the shaft 9.

What I claim is:

1. In an oscillatory drive for a sliver receiving can, a revoluble carrier for bodily carrying the can, a revoluble mangle rack in the form of a split annulus provided with a pair of spaced endless rows of teeth merging into each other, a slidably suspended driven means automatically bodily movable in a rectilinear path alternately coacting with said rows of teeth for revolving said rack successively clockwise and anti-clockwise and for reversing the direction of movement of the rack when the latter completes substantially a revolution, and an operable driving connection 60 for said carrier operated from the rack, interposed between said rack and carrier and providing for the latter revolving in a direction corresponding to the direction of movement of the rack.

2. In an oscillatory drive for a sliver receiving can, a revoluble carrier for bodily carrying the can, a revoluble mangle rack in the form of a split annulus provided with a pair of spaced endless rows of teeth merging into each other,

automatically vertically movable driven means alternately coacting with said rows of teeth for revolving said rack successively clockwise and anti-clockwise and for reversing the direction of movement of the rack when the latter completes substantially a revolution, an operable driving connection for said carrier and providing for the latter revolving in a direction corresponding to the direction of movement of the rack, said driven means including a combined guide and retaining roller, and a combined guide and retaining structure fixed to said rack and said driving connections and permanently bearing against said roller.

3. In an oscillatory drive for a sliver receiving can, a revoluble carrier, for bodily carrying the can, a revoluble mangle rack in the form of a split annulus provided with a pair of spaced endless rows of teeth merging into each other, a slidably suspended driven means automatically bodily movable in a rectilinear path alternately coacting with said rows of teeth for revolving said rack successively clockwise and anti-clockwise and for reversing the direction of movement of the rack when the latter completes substantially a revolution, an operable driving connection for said carrier, a combined guide and retaining structure for said means fixed to and bodily carried with the rack, said structure being fixed to said driving connection for operating the latter, and the parts of said driving connection being so related to provide for the carrier revolving in a direction corresponding to the direction of movement of the rack.

4. In an oscillatory drive for a sliver receiving can, an oppositely revoluble drive for the can, an oppositely revoluble mangle rack of annular form for operating said drive, a bodily slideable suspended driven means for revolving said mangle, said means and mangle having coacting parts for reversing the direction of movement of the mangle after each substantially complete revolution of the latter, and operating means for the means for revolving the rack, the said driven means for revolving the rack being suspended by and slidably mounted on said operating means for automatic vertical movement bodily in opposite directions on said operating means.

5. In an oscillatory drive for a sliver receiving can, an oppositely revoluble drive for the can,

an oppositely revoluble mangle rack of annular form for operating said drive, a suspended oppositely bodily slideable driven means for revolving said mangle, said means and mangle having coacting parts for reversing the direction of movement of the mangle after each substantially complete revolution of the latter, and a combined guide and retainer structure fixed to and bodily movable with the rack and coacting with a part of said means for permanently guiding and maintaining such means in slideable toothed engagement with the rack.

6. In an oscillatory drive for a sliver receiving can, an oppositely revoluble drive for the can, an oppositely revoluble mangle rack for operating said drive, a slideably suspended driven means automatically bodily movable in a rectilinear path for revolving said mangle, said means and mangle having coacting parts for reversing the direction of movement of the mangle after a substantially complete revolution of the latter.

7. In an oscillatory drive for a sliver receiving can, an oppositely revoluble gear train drive for the can, said train being located below the bottom of and extended in lateral relation with respect to the can, an oppositely revoluble mangle rack for operating said train located adjacent the can and arranged over and connected to one of the gears of the train for operating the latter, a suspended oppositely bodily slideable driven means, said driven means and mangle having coacting parts for revolving the mangle and for reversing the direction of movement of the mangle after a substantially complete revolution of the latter, said driven means having slideable toothed engagement with the rack, operating means for said driven means to provide for the revolving of the rack, the said driven means being suspended by and slideably mounted on said operating means for automatic vertical movement bodily alternately in opposite directions, and a combined guide and retainer structure fixed to and bodily movable with the rack and coacting with a part of the driven means for permanently guiding and retaining the latter in slideable toothed engagement with the rack.

BALDY McGINNIS.
